G. E. FOX

PROCESS OF TRANSFERRING GASES AND VAPORS

Filed Dec. 9, 1925

GEORGE E. FOX Inventor

By his Attorney, *C. M. straw.*

UNITED STATES PATENT OFFICE.

GEORGE E. FOX, OF ELIZABETH, NEW JERSEY, ASSIGNOR TO STANDARD OIL DEVELOPMENT COMPANY, A CORPORATION OF DELAWARE.

PROCESS OF TRANSFERRING GASES AND VAPORS.

Application filed December 9, 1925. Serial No. 74,256.

This invention relates to improvements in the transfer of gaseous or vaporous hydrocarbons and comprises the use of relatively high pressure hydrocarbon gas or vapor as the transfer agent. For brevity in the subsequent description and in the claims, reference will be made to hydrocarbon gas, it being understood that this term as used herein covers hydrocarbon vapors also, whether associated or not with liquid hydrocarbons.

The invention will be fully understood from the following description, taken in connection with the accompanying drawing, in which

Fig. 1 is a vertical section of one form of injection apparatus; and

Fig. 2 is a diagrammatic side elevation of hydrocarbon cracking equipment, in which my improved transfer process is utilized.

Referring first to Fig. 1, reference numeral 1 denotes a conduit or pipe of relatively large diameter, having a constriction 2 therein. A pipe 3 of smaller diameter enters the conduit 1 and has its delivery end 4 turned in the direction of the flow of gas through the conduit. The pipe 3 is connected with a supply of hydrocarbon gas under pressure, for example a gas compressor, an oil refinery "high line" receiving high pressure gas from pressure stills and the like, or other suitable source. The conduit 1 is connected to a source of the low pressure gas which it is desired to transfer. The gas may be allowed to expand adiabatically from the pipe 3, or heating means may be provided to counteract the cooling incident to expansion or to raise the gas to any desired temperature.

In Fig. 2 there is illustrated cracking equipment, comprising a heating coil 5 arranged in a suitable furnace setting 6, and a digesting chamber or soaking drum 7. The drum may have thermal insulation 8, or it may be jacketed with flue gases or otherwise protected against substantial temperature loss. A pipe 9 connects the coil and drum. In this pipe an injection device or nozzle 10, having a constriction 11, is installed.

A compressor 12 forwards gas under high pressure through pipe 13 to the injection device 10. A coil 14 may be included in the pipe 13 and arranged in a furnace 15, so that the gas may be supplied at the desired high temperature. The hydrocarbon gas to be injected may be obtained from any suit-

able source. When the system is in full operation, sufficient gas for injection purposes will ordinarily be produced in it. This gas may be forwarded to the compressor through pipe 16 which is connected to a receiver 17. Condensate from a cooling coil 18, supplied with vapors from the upper portion of vapor separator or bubble tower 19, flows into this receiver. The gas accompanying the condensate, if not all utilized for injection purposes as described, will be withdrawn to storage or other suitable disposition, through pipe 17a.

The bubble tower may have a cooling coil 20 in its upper portion. A collecting pan 21 receives condensate which is withdrawn through pipe 22 for return to the system or for other suitable disposition. A pipe 23 for drawing off residuum is connected to the lower portion of the tower. A pipe 24 conveys the product from the soaking drum 7 to the lower portion of the tower. A pressure-regulating valve 25 is installed in the pipe 24. Another pressure-regulating valve 26 may be placed in a vapor line 27 leading from the tower.

The following example is illustrative of one embodiment of my invention: The oil to be cracked is fed into the coil 5 which is maintained at a temperature of about 680° to 700° F. and under a pressure of less than 50 lbs. per square inch, preferably about 25 lbs. per square inch. Under these conditions a substantial proportion of the oil is vaporized in the coil. The rate of flow through the coil is preferably so rapid that little, if any, cracking and coke formation take place therein. The oil passes from the coil through pipe 9 into the injection device 10. Gas under high pressure, preferably about 1000 lbs. per square inch, is supplied from the compressor 12. Mingling with this gas in the injection device, the low pressure vapors and liquids from the heating coil 5 are carried through the constricted passage 11 and into the drum 7 in which a pressure of about 350 lbs. is produced. In this way I am able to increase greatly the pressure upon the vapors issuing from the heating coil, without the use of a pump. As is well known, difficulties are frequently encountered when using pumps for transferring oil under high pressure and temperature. The momentary constriction of the gas flow is an important feature of the invention, as

by it there is obtained what I believe to be an actual compressive effect upon the low pressure vapor.

The high pressure gas is preferably heated 5 to about 900° F. in the heater 15. In the drum 7 conversion of the oil takes place and the vaporous and liquid products together are taken off through the pipe 24 to the bubble tower 19, the pressure being relieved at 10 valve 25 to any desired extent. Preferably the bubble tower is operated at 60 lbs. pressure or less, and this pressure may be controlled by the valve 26. The vapors are taken off from the upper portion of the 15 tower for condensation, and the residuum or tar is drawn off from the bottom as required.

The use of my invention permits the avoidance of mechanical pumps for the 20 transfer of oil from heating coils to digesting chambers. Gas injection in the manner described is a reliable and economical method for producing the desired pressure in a digesting chamber operated in connection with a vapor phase or semi-vapor phase 25 heating coil.

My invention is not restricted in its application to the particular apparatus just described. It may be used in a variety of 30 other connections, for example in accelerating the flow of gas through a refinery, "low line" receiving gas at low pressure, for transferring still vapors through a bubble tower, or for other purposes.

35 The procedures described are illustrative

of preferred forms of the invention, but various modifications may be made within the scope of the appended claims, in which it is my intention to claim all novelty inherent in the invention as broadly as the prior art 40 permits.

I claim:

1. Process of transferring hydrocarbon vapors from a heating coil to a digesting zone in which conversion takes place, comprising passing the vapors from the coil at relatively low pressure into a conduit, injecting into the conduit in the direction of travel a stream of gas at high pressure, constricting the flow of the vapors and gas, and 50 then allowing the stream to expand into the digesting zone under a pressure materially higher than that prevailing in the coil.

2. Process of transferring hydrocarbon vapors from a heating coil to an enlarged 55 digesting zone in which conversion takes place, comprising passing into a conduit the product from the coil partly in vapor phase and at a pressure not in substantial excess of 50 lbs. per square inch, injecting into the 60 conduit in the direction of travel a stream of gas at a pressure approximating 1000 lbs. per square inch, constricting the flow of the gas for a brief period, and then allowing expansion into the enlarged chamber, whereby the low pressure vapors are forced into 65 such chamber and subjected to a pressure of the order of 350 lbs. per square inch therein.

GEORGE E. FOX.
